HIGH SPEED SYNCHRONIZED WINDER

Eugene F. Monnia and John W. Mills,
Scranton, Pa.

Application June 17, 1939, Serial No. 279,640

2 Claims. (Cl. 242—18)

This invention relates to winding devices used in textile and other industries where filament or strand material, such as thread, yarn, cord and the like, is wound on suitable instrumentalities, such as bobbins, spools, spindles and the like, from quantities or skeins of the indicated material.

The principal object of the invention is the provision of a winding device or unit of the character mentioned, which is adapted to hold the material stationary in the form of a coil, and unwind the same therefrom and synchronously wind it on the desired instrumentality.

Some of the features and advantages of the invention are as follows: It is possible to operate at high speed without increasing the tension of the strand. The winding speed of the strand does not increase the tension, therefore, the tension may be easily controlled and regulated. A skein in the form of a coil may be held on an open sided swift from which it may be unwound without rotating the swift. It is possible to obtain a better grade of wound yarn as said yarn receives a more uniform tension. Due to its adaptation for maintaining the desired and uniform tension of the thread or yarn, it is possible to transfer the thread or yarn from skein to bobbin faster than at present, while decreasing the amount of waste material, lessening breakage per skein, obtaining uniformity of thread or yarn, eliminating soft bobbins, and consequently reducing operation and labor costs.

In the drawings to which reference is made in the following specification—

Fig. 1 is a fragmentary side view partly in section of a machine embodying the winding device of the present invention;

Fig. 2 is a front view partly in section; and

Fig. 3 is a side view of the unwinder detached.

Referring now more particularly to the drawings, it will be apparent that there is illustrated parts of a conventional machine adapted to wind yarn on a bobbin from a skein and the same being selected to show the device of the present invention applied thereto. The machine includes a drive shaft 10 and stationary horizontal rails 11 and 12. A plate 13 is fixed on the rail 11. This plate has spaced apertured lugs 14 integral therewith and brackets 15 are respectively pivotally connected with said lugs 14, as at 16, so that they are free to pivot up and down. The brackets 15 carry a bobbin 17, the trunnions 18 of the latter being respectively received in notches 19 or 20 in the brackets. Therefore, the bobbin may move up and out as the yarn is wound

on it increasing the diameter. A two-part shaft 21 is supported by bearings carried by the brackets 15. A bobbin driving roll 22 is fast on the shaft parts 21 between the brackets 15. The roll 22 has a hub 23 and a V groove pulley 24 integral therewith or secured thereto on one end. A grooved pulley 25 is fast on the drive shaft 10. A rubber ring 26 is disposed in the groove in the pulley 25 and is cemented to the latter. This ring 26 constitutes a friction means which contacts the walls of the V groove in the pulley 24 to impart rotary motion to the pulley 24 in response to the rotation of the pulley. This will cause the rotation of the roll 22. The cylindrical surface has applied thereto cork or other friction material to provide a cylindrical friction surface to contactually engage the cylindrical surface of the bobbin 17 or the windings of yarn wound thereon, in order to rotate the bobbin in the yarn winding operation.

A traversing and tensioning means 27 serves to guide the yarn under tension to the bobbin.

A counterbalanced stop motion 28 is operatively carried by a bracket 29 extending forwardly and downwardly from the plate 13. This stop motion 28 includes a porcelain eye 30 through which the yarn passes to the means 27. If the yarn breaks the stop motion 28 cooperates with the hub 23 to lift the pulley 24 out of frictional engagement with the ring 26, thereby stopping the rotation of the bobbin 17.

The means 27 and 28 are conventional and no claim is made herein to the specific features thereof.

In accordance with the invention, use is made of a suitable holder for the material, such as the yarn mentioned hereinabove, by way of example. The holder may advantageously consist of a circumferentially adjustable swift 31 of open sided type, as shown most clearly in Fig. 2. For this purpose a bracket 32 is secured to the rail 12 and rises therefrom. A sleeve 33 has one end secured to the bracket 32 so as to project horizontally therefrom. The hub of the swift 31 has a frictional fit on the sleeve 33 and, therefore, holds the swift 31 stationary during normal winding operation, but it may be manually rotated to permit mounting of skeins and tying of yarn ends. Roller bearings 34 are positioned respectively in the opposite ends of the sleeve 33 and these bearings support a shaft 35. A grooved pulley 36 is fast on one end of the shaft 35 and a grooved pulley 37 is fast on the shaft 21. A rubber belt 38 encircles the pulleys 36 and 37. Rotary motion is therefore transmitted to the shaft 35.

from the shaft 10 through the intervention of the pulley 25, pulley 24, shaft 21, pulley 37, belt 38 and pulley 36. The belt being of rubber and therefore elastic allows the stop motion 23 to function to stop the rotation of the bobbin.

In accordance with another feature of the invention a traveler is provided to unwind the yarn from a skein held stationary on the swift 31. This traveler rotates with the shaft 35 as driven by the pulleys 36 and 37 and the belt 38. The traveler consists of a disk 39, radial member 40, take-up eye 41 and central let-off eye 42. The disk 39 is secured to the end of the shaft 35 remote from the pulley 36. The member 40 consists of a wire which is flattened near its inner end as at 43 and this flattened portion has holes therein to accommodate suitable fastening elements 44 which securely fasten the member 40 to the disk 39. The take-up eye 41 is formed on the outer end of the member 40 from the material of the wire stock and is left open so that the yarn may be engaged therein. The let-off eye 42 is also formed on the inner end of the member 40 from the material of the wire stock and is also left open for engaging the yarn therein. The let-off eye 42 is disposed concentric to the axis of the shaft 35. The member 40 is disposed radially at the open side of the swift 31 and is sufficiently long to bring the take-up eye 41 beyond the skein carriers of the swift.

A skein of yarn or any other filament or strand material is held stationary in a coil by the swift 31 and the yarn is passed through the eye 41, thence is brought inwardly toward and through the eye 42, thence upwardly through the eye 33, beyond which it is engaged by the tensioning and traversing means 27 and finally fastened to the bobbin on which the yarn is wound. The yarn is designated 45.

40 The skein (not shown) remains stationary on the swift 31 and the yarn is unwound by the revolving power driven traveler that takes the yarn from the skein and carries it out through the central eye 42 up to the bobbin 17 on which it is wound, permitting a comparatively high operating speed because the tension remains uniform at any speed. The yarn is thus unwound or paid out freely from the source of supply and wound on the bobbin in synchronism. It is, therefore,

possible to attain all of the advantages hereinbefore mentioned.

In many instances the use of the pulleys 24 and 36, as well as belt 38, is desirable. In some cases, however, these pulleys and belt 38 may be eliminated and the yarn fed directly to the winding spool from the arm 40. When the belt 38 and associated parts are eliminated, a pull of the yarn on the arm 40 will cause the same to rotate and thereby feed the yarn properly to the winding 10 spool.

15 It is to be understood that the invention is not restricted to the precise embodiment thereof as illustrated and described, but that details of construction may be modified and rearranged without departing from the spirit of the invention as defined in the claims.

We claim:

1. In a winder for winding strand material, the combination of a driven shaft, means rotatable 20 with said shaft including an arm having guide eyes which pass the strand of material from a source of supply surrounding said shaft to a suitable receiver on which the material is to be wound; said means serving to unwind the material from said source, a driving roll for rotating the receiver, and common means for rotating the shaft and roll simultaneously.

25 2. A device of the character described comprising a bracket, a tubular member having one end fitting snugly in said bracket and held stationary thereby, a swift having a tubular hub fitting over part of the tubular member and held stationary thereby, a rotatable shaft extending through said tubular member, power driven means for rotating said shaft, an arm formed at each end with an eye, said arm near one of said eyes having an apertured enlargement for receiving the end of said shaft, means for clamping said enlargement to said shaft so that the eye adjacent the enlargement will be in axial alignment with the shaft, the other eye being positioned radially outwardly from the periphery of the swift and slightly to one side thereof, said arm rotating with said shaft so that the eye near the periphery of the swift may 40 unwind yarn from the shaft by a lifting action, said yarn being guided by the respective eyes to a point of utilization.
